TUBE EXTRACTING DEVICE

Robert W. Clark, Port Washington, N. Y., assignor to Radio Corporation of America, a corporation of Delaware

Application November 29, 1944, Serial No. 565,663

8 Claims. (Cl. 81—3)

1

The present invention relates to an instrument for quickly and easily removing from its socket a device such as an electronic discharge tube.

In designing radio sets and other electronic assemblies, it is often necessary to position one or more sockets so that the particular tube, transformer, or other circuit component receivable therein is not conveniently accessible by hand in the event that its removal is desired for purposes of inspection or replacement. Furthermore, in the case of a tube or other member which becomes heated during operation of the assembly, it cannot be removed by hand until after a cooling period regardless of its location.

The principal object of the present invention, therefore, is the provision of an instrument for removing from its socket a circuit element which cannot be conveniently removed by hand.

A further object of the invention is the provision of an extracting tool which may be slipped over a tube or other plugged-in device, the tool then being subjected to a manual squeezing action which causes it to grip the plugged-in device in such a manner that the latter may be withdrawn from its socket by a simple pulling movement of the tool.

A still further object of the invention is the provision of an instrument which may be employed to remove from its socket a tube which is held therein by a snap clip or other resilient retaining means lockably engaging a flange on the tube.

Other objects and advantages will be apparent from the following description of preferred forms of the invention and from the drawings, in which:

Fig. 1 is a side view in elevation of a preferred form of extracting tool in accordance with the present invention;

Fig. 2 is an end view of Fig. 1;

Fig. 3 is a section along the line 3—3 of Fig. 1;

Fig. 4 is a side view in elevation of a modification of the extracting tool of Fig. 1, also showing one form of device with which the modified extracting tool may be employed;

Fig. 5 is an end view of a portion of Fig. 4;

Fig. 6 is a view of a portion of Fig. 4 showing the method of operation of the extracting tool; and

Fig. 7 is a modification of Fig. 5.

In the form of the invention illustrated in Figs. 1 to 3, there is shown an extracting tool including a hollow cylindrical member 10, such for example as a section of metal tubing, which has cut out therefrom two diametrically-opposed longitudinal openings 12 and 14. These openings 12 and 14 extend for nearly the entire length of the

2

member 10, leaving only a small uncut portion 16 at one end thereof, and, except for the end portion 16, effectively transform the tubular member 10 into two oppositely-disposed arcuate strips 18 and 20.

At the opposite end of arcuate strips 18 and 20 from the uncut portion 16 is a ring-shaped member 22 which has its inner surface soldered or otherwise securely affixed to the outer surface 10 of the strips. The inner diameter of ring-shaped member 22 is slightly greater than the outer diameter of the uncut end 16, so that the strips 18 and 20 taper outwardly to a slight extent from end 16 toward the ring member 22.

15 An alternative construction to the above would comprise two ring-shaped members of different internal diameters respectively secured to the ends of two oppositely-disposed arcuate strips. Such a construction would eliminate the necessity of utilizing a tubular member, as flat strips could be employed which have been bent into arcuate shape.

20 Slidably carried by the arcuate strip 20 is a clutch element 24. This sliding clutch element 25 24 may comprise a single sheet of metal which is shaped approximately to fit the curvature of the arcuate strip 20, as illustrated in Figs. 2 and 3. A member 26 of suitable thickness, also shown in Figs. 2 and 3, is securely affixed in surface-to-surface relation to the mid-portion of the clutch element 24, and as shown in Figs. 2 and 3 may lie between such mid-portion and the concave inner surface of the arcuate strip 20. The combined thickness of elements 24 and 26 acts to prevent 30 excessive distortion of the arcuate strips 18 and 20 when the clutch element 24 is brought into engagement with the device being extracted, as will now be described.

35 In operation, the clutch element 24 is slid along 40 strip 20 to one end of the extracting tool. Either end may be used, depending upon the dimensions of the tube or other circuit element to be extracted. The end of the tool to which the clutch element 24 has been moved is then slipped over 45 the tube as far as it will go, and the arcuate strips 18 and 20 are squeezed together. This causes the clutch element 24 and arcuate strip 18 to be brought into frictional engagement with the tube, and if the squeezing pressure is sufficient 50 the tube may be easily removed from its socket by a simple pulling or lifting movement of the tool.

The extracting tool is, of course, constructed so that its dimensions are suitable for the particular circuit elements, such as tubes, plug-in

resistors, condensers, and the like, with which it is to be used, the internal diameter of each end of the tool, including the clutch 24, being slightly greater than the external diameter of the element to be extracted by that end. For example, if the internal diameter of end 16 is $1\frac{1}{8}$ ", and if clutch element 24 projects radially inward for a distance of $\frac{1}{8}$ " from the inner surface of member 10, then that end of the extracting tool may be employed to remove from its socket a metal tube with an M8 shell, such as the RCA 6AC7.

In the event that a particular circuit component would be accommodated by either end of the tool except for the restriction offered by the clutch 24, the latter may be slid to the far end of the tool and the ring 16 or the ring 22 slipped over the circuit element so that both strips 18 and 20 are in direct contact therewith. Furthermore, if the inner surface of arcuate strip 18 near the end 16 is coated with a substance that has a relatively high coefficient of friction, such for example as that material known commercially as "flock," then that end becomes more suitable for extracting devices that have a glass envelope or other smooth surface. The inner, or article-contacting, surface of clutch element 24 may likewise be coated with such a substance so as to provide a more positive gripping action.

Occasionally, however, tubes are provided with a flanged base, and snap clips or other resilient means which are mounted on the chassis engage the flange to lock the tube in position. A modification of the extracting tool of Figs. 1 to 3 so as to permit removal of tubes which are locked in place in this manner is shown in Figs. 4 to 6.

Fig. 4 shows a tube 28 the base of which is provided with a flange 29. A pair of snap clips 30 mounted on chassis 32 engage flange 29 to lock tube 28 in position. Secured to the end of the extracting tool being utilized, such as the end 16, are two oppositely-disposed tabular projections 33, shown also in Fig. 5. These tabular projections 33 have sufficiently large radial dimensions that when the extracting tool is pushed down over tube 28, the tabular projections 33 force the clips 30 outwardly, disengaging them from the flange 29 as shown in Fig. 6, and allowing the tube to be lifted out of its socket in the manner described above in connection with Figs. 1 to 3.

If desired, a ring 34 such as shown in Fig. 7 may be employed in place of the tabular projections 33, this ring 34 being secured to either end of the extracting tool and having an outer diameter slightly larger than the flange 29. The ring 34 may also comprise merely an integral radial extension of that particular end of the tool. Operation of the modification shown in Fig. 7 is similar in all respects to that of the device of Figs. 4 to 6, except that the necessity of lining up the tabular projections 33 with the clips 30 is eliminated.

While I have described above an extracting tool which is suitable for use with circuit elements of various diameters, it will be understood that when a tool of this type is designed especially for use with a single device or a number of devices having similar diameters, or in other words when only the uncut end 16 of the tool is to be used, then it is unnecessary to encircle the slotted end of the tool with the ring-shaped member 22 and this latter member may be omitted.

I claim:

1. In a device of the class described, a tubular member having a plurality of cut-out portions extending longitudinally thereof to one end of

said member, said cut-out portions dividing said tubular member into a plurality of strips, an article-engaging member carried by one of said strips, said article-engaging member being slideable along said one strip toward either end of said tubular member, and a ring-shaped element encircling said strips at said one end of said tubular member, said ring-shaped element having an inner diameter greater than the outer diameter of said arcuate tubular member, and means securing the inner surface of said ring-shaped element to the outer surface of said strips.

2. In a tool for extracting from its socket a device of substantially annular cross-section, the combination of a hollow substantially cylindrical member having an internal diameter slightly larger than the external diameter of said device, said hollow cylindrical member having a plurality of linear axial slots formed therein extending from one end of said member to a point near the other end of said member, a ring-shaped element having an internal diameter greater than the external diameter of said hollow cylindrical member encircling said member at the slotted end thereof, said ring-shaped element having its inner surface secured to the outer surface of said slotted cylindrical member so that the latter tapers outwardly toward the ring-encircled end thereof, and clutch means slidably mounted on one of the longitudinal sections of said cylindrical member formed by said slots, whereby, when the end of said hollow cylindrical member including said clutch means is slipped over said device, a radial inward pressure on the longitudinal sections of said cylindrical member will cause said clutch means to frictionally engage said device.

3. A tool according to claim 2 for extracting from its socket a device of annular cross-section having a flange thereon which is lockably engaged by one or more spring clips, further comprising one or more tabular projections mounted on one end of said cylindrical member and positioned for respective contact with said spring clips when the end of said cylindrical member mounting said tabular projections is slipped over said device.

4. A tool according to claim 2 for extracting from its socket a device of annular cross-section having a flange thereon which is lockably engaged by one or more spring clips, further comprising a ring-shaped projection mounted on one end of said cylindrical member, said projection having an outer diameter greater than the outer diameter of the flange on said device and being positioned for contact with said spring clips when the end of said cylindrical member mounting said ring-shaped projection is slipped over said device.

5. In a device of the class described, a pair of spaced-apart oppositely-disposed arcuate strips arranged to outline in cross-section two segments of a circle, a pair of ring-shaped members of different internal diameters respectively secured to the ends of said arcuate strips, and an article-engaging element carried by one of said arcuate strips, said article-engaging element being slideable along said one arcuate strip toward either ring-shaped member.

6. In a device of the class described, a plurality of strips of material arranged in spaced-apart relation so that the longitudinal axes of said strips are inclined toward each other, a pair of positioning members, said positioning members respectively rigidly securing in spaced-apart re-

lation the adjacent ends of said strips, and an article-engaging element carried by one of said strips, said article-engaging element being slideable along said one strip toward either of said positioning members.

7. In an instrument for selectively extracting substantially cylindrical plugged-in devices having different external diameters, the combination of a pair of spaced-apart oppositely-disposed arcuate strips arranged to outline in cross-section two segments of a circle, a ring-shaped member, means securing said ring-shaped member to the adjacent ends of said pair of arcuate strips, whereby said ring-shaped member may be slipped over a substantially cylindrical plugged-in device which has an external diameter smaller than the internal diameter of said ring-shaped member, a second ring-shaped member having an internal diameter larger than the internal diameter of said first-mentioned ring-shaped member, and means securing said second ring-shaped member to the other adjacent ends of said pair of arcuate strips, whereby said second ring-shaped member may be slipped over a substantially cylindrical plugged-in device having an external diameter larger than the internal diameter of said first-mentioned

ring-shaped member, and whereby, when either of said ring-shaped members is slipped over a plugged-in device, a radial inward pressure on said arcuate strips will cause said strips securely to grip said device and permit the extraction thereof.

8. An instrument according to claim 7, further comprising an arcuate element slidably carried by one of said spaced-apart arcuate strips, said arcuate element being designed for movement selectively along said one arcuate strip toward one of the two said ring-shaped members which is slipped over a plugged-in device.
